SELECTING SYSTEM

Application filed January 23, 1929. Serial No. 334,579.

This invention relates generally to systems for effecting selective operation or control of apparatus. It has particular application to systems effecting selective control in response to the human voice.

It is a general object of this invention to devise a novel form of selecting system, utilizing marginally operated electron relays.

It is a further object of this invention to devise a selecting system in which a plurality of marginally operated relays are so interrelated as to cause operation of only one relay in response to controlling energy of a certain magnitude.

It is a further object of this invention to devise a novel system and method of interlocking electron relays, whereby actuation of one relay causes blocking of one or more other relays of the system.

It is a further object of this invention to devise a novel system for effecting selective operation of printing apparatus according to spoken sounds.

Further objects of the invention will appear from the following description in which I have set forth the preferred embodiments of my invention. It is to be understood that the appended claims are to be accorded a range of equivalents consistent with the state of the prior art.

Attention is directed to the accompanying drawings in which:

Fig. 1 is a circuit diagram illustrating one embodiment of my invention.

Figs. 2, 3, and 4 are circuit diagrams illustrating other embodiments.

My system consists generally of a plurality of relays designated 11, 12 and 13, which are connected to a common control circuit 10. The relays serve to effect selective operation of an apparatus designated generally at 14, this apparatus being connected to the relays thru a plurality of response circuits 21, 22 and 23. The relays which I employ are preferably of the electron relay type, and for a purpose which will be presently explained, I prefer in this embodiment to utilize relays of this character having a plurality of control elements or grids. Thus each relay is shown as consisting of a cathode 26,

anode 27 and control elements or grids 28 and 29. As is customary in such relays, these elements are enclosed in an evacuated vessel.

Control circuit 10 is connected to the input of each relay. For example as shown one side of circuit 10 is connected to one of the control elements, say element 28, of each relay, and the other side of circuit 10 is connected to the cathodes 26. The grids 28 of each relay are negatively biased for marginal operation, and for this purpose I have indicated C-batteries 41, 42 and 43. C-batteries 41, 42 and 43 are of such values that normally the plate current of each relay is reduced to substantially zero when no potential difference is impressed across control circuit 10. However one of the relays, say relay 11 has a C-battery of such a value that its plate current will assume an appreciable value for a certain potential difference placed across the control circuit 10, while the C-batteries 42 and 43 are such that the plate currents of the corresponding relays remain at zero value for such controlling potential. The C-battery for another relay, say relay 12, is of such value that for a substantially greater controlling potential, the plate current of this relay will assume a substantial finite value, while the plate circuit of relay 13 is still substantially zero. For a still greater controlling potential, the plate circuit of relay 13 assumes a substantial finite value together with plate circuits of relays 11 and 12.

Without additional means other than that which has been described above, it is evident that because of the marginal biasing of relays 11, 12 and 13, one relay, say relay 11 will respond to a controlling potential of a certain magnitude to effect closing of magnetic relay 32, while for a second controlling potential both relays 11 and 12 would be operated, and for a third potential value, all three relays would be operated simultaneously. For the purposes of my invention it is desirable to effect operation of only one relay in response to a controlling potential of a certain value. As a means for effecting this result, I provide a connection between the output of one relay and

the input of a preceding relay. For example in series with the plate circuit of relay 12 I have shown a resistance 44. That terminal of this resistance which is connected to B-battery 31 is connected to the controlling element 29 of relay 11 thru conductor 46, while the other terminal of resistance 44 is connected to cathode 26 of relay 11 thru conductor 47. Relay 13 is similarly provided with a resistance 44 having its terminals connected across control element 29 and cathode 26 of relay 12. As will be presently explained this connection between the relays causes relay 11 to be blocked when relay 12 is operated.

In combination with the relay arrangement described above, I preferably provide a suitable source of electrical current variations formed according to spoken sounds. Thus I have shown a circuit 48 including a microphone 49 or some other such device which will serve to translate sound into current variations. Circuit 48 is shown coupled to a suitable amplifier 50, which in turn has its output coupled to the control circuit 10 thru suitable integrating means 51. Means for securing a direct integrated current from current variations is well known in the art, and may consist of a current rectifier in conjunction with a reactive filter.

It is well known that different sounds of the human voice, as for example sounds corresponding to the different vowels of the English language, have decidedly different wave forms. I have discovered that when these wave forms are duplicated by electrical current variations in an electrical circuit, that the integrated direct current components of such current variations also have characteristic magnitudes, depending upon the character of sound setting up the current variations. Thus if different vowels such as a, o, and i are spoken into the microphone 49 of circuit 48, and the loudness or intensity of each sound is practically the same, direct integrated currents of different magnitudes will be impressed upon the control circuit 10, depending upon which vowel is being spoken.

The translating apparatus 14 may be any means which is capable of being selectively operated by the response circuits 21, 22 and 23. For example this apparatus may be a printer having solenoids or magnets for operating type bars, these solenoids or magnets being energized or controlled from the response circuits. In such case when any one response circuit is closed, a corresponding printed character is made by the apparatus 14.

In explaining the operation of the above system, it will be assumed that a certain vowel, say the vowel "a" is spoken into the microphone 49. It is also presumed that the electron relays 11, 12 and 13 are ad-

justed, by having relays of different characteristics or by providing C-batteries 41, 42 and 43 of different voltages, so as to respond respectively to potentials of magnitude values 1, 2 and 3 respectively. It is presumed that when different sounds are spoken into the microphone 49, as for example the vowels a, o and i, the corresponding integrated potentials impressed upon the control circuit 10 will have magnitude values 1, 2 and 3 respectively.

When a potential of magnitude 1 is impressed upon control circuit 10 by speaking the vowel a into the microphone, the grids 28 of all the relays are made more positive by a certain amount.

The biasing of relays 12 and 13 is such however that even with grids 28 of these relays made more positive in this manner, the plate currents of these relays will remain practically zero. Relay 11 however is adjusted so that when its grid 28 is made more positive by this amount, the plate current of this relay is made sufficient to cause operation of the corresponding magnetic relay 32, to close response circuit 21.

Now if a potential of magnitude value 2 is impressed upon the control circuit 10, as by speaking the vowel o into the microphone 49, the grids 28 of the relays are made more positive by a greater amount, and relay 12 is adjusted so that its plate circuit now increases to a value sufficient to cause operation of magnetic relay 32. However the grid 28 of relay 13 is biased to such an extent that it is unaffected by such a controlling potential.

When the plate circuit of relay 12 increases to such an extent as to cause operation of its magnetic relay 32, a substantial potential difference occurs across the resistance 44. The connection between this resistance and relay 11 is such that grid 29 of relay 11 is made more negative to cause the plate current of relay 11 to assume practically zero value in spite of the potential of grid 28.

In other words relay 11 is blocked by a controlling potential placed upon the grid 29. Thus upon operation of relay 12, relay 11 is blocked in such a manner as to release its corresponding magnetic relay 32 and to open its response circuit 21.

When the potential of magnitude 3 is impressed upon control circuit 10, the grids 28 of the relays are again made more positive to a greater extent. The adjustment of relay 13 is such that this relay is now operated as its plate current increases to an extent sufficient to cause operation of its corresponding magnetic relay 32.

A potential difference is likewise formed across the resistance 44 of this relay, and because of the connection between this relay and the grid 29 of relay 12, relay 12 is blocked to cause release of its corresponding magnetic relay 32.

Upon blocking of relay 12, its plate cur-

rent is increased to a value sufficient to cause operation of its magnetic relay 32. A potential difference is likewise formed across the resistance 44 of this relay, and because of the connection between this relay and the grid 29 of relay 12, relay 12 is blocked to cause release of its corresponding magnetic relay 32.

Upon blocking of relay 12, its plate cur-

rent is made substantially zero, and a potential difference no longer exists across the resistance 44. Therefore unless adequate means is provided, actuation of relay 13 also is accompanied by actuation of relay 11. One means to prevent actuation of relay 11 is to provide a third control element 52 which has its grid connected to the grid 29 of relay 12. The potential thus impressed upon grid 52 is sufficient to block relay 11 and prevent its actuation.

Another method of preventing actuation of response circuit 21 during actuation of relay 13 is to provide an additional relay 61 cascaded with relay 11. The output circuit of this relay is connected to magnetic relay 32 and its cathode and grid 28 are connected across a resistance 62 inserted in the plate circuit of relay 11. Grid 28 is properly biased so that its plate current is finite only when a plate current flows in relay 11. A second grid 29 of this relay is connected to grid 29 of relay 12. Therefore relay 61 is blocked upon actuation of relay 13, and thereby prevents actuation of response circuit 21 at this time.

In Fig. 3 I have shown a further modification in which simplified means is provided for interlocking the various electron relays. Thus I have shown electron relays 11, 12 and 13 having their grids 28 connected to control circuit 10, and marginally biased as described with reference to Fig. 1. Grids 29 of these relays are connected to a common conductor 64, which is also connected to the high potential terminals of resistances 44. For a purpose to be presently explained, biasing or "C" batteries 66 are shown connected in series with the grids 29 of relays 12 and 13.

With the arrangement shown in Fig. 3, when a controlling potential of magnitude 1 is impressed upon circuit 10, relay 11 is operated to the exclusion of relays 12 and 13. When a potential of magnitude 2 is impressed upon circuit 10, the plate circuits of both relays 11 and 12 become of finite value, and the potential drop across resistances 44 impresses a blocking negative potential upon grid 29 of relay 11, thus rendering this relay inoperative. It is to be noted that at this time resistances 44 of relays 12 and 13 are connected together in parallel, since the cathodes of relays 12 and 13 are conductively connected together. The purpose of battery 66 is to so marginally bias grid 29 of relay 12, that the drop in potential across resistances 44 encountered at this time will not block this relay itself. When a potential of magnitude 3 is impressed upon circuit 10, the plate current of relay 13 is made of finite value and the potential drop across resistances 44 is made greater. C-battery 66 of relay 12 is of such value that at this time the potential on its grid 29 is sufficient to effect

blocking of the same as well as blocking of relay 11.

In Fig. 4 I have shown a further modification of my invention in which the different electron relays or equivalent devices are electromagnetically interconnected. In this case I can employ ordinary three element electron relays 71, 72 and 73, having their grids marginally biased and connected to the control circuit 10. An electromagnetic relay 81 has one winding 74 which is included in the plate circuit of relay 71, and another winding 75 included in the plate circuit of relay 72. Another similar electromagnetic relay 82 has its corresponding winding 74 included in the plate circuit of relay 72, and its other winding 75 included in the plate circuit of relay 73. A third electromagnetic relay 83 has a single winding 74 connected in the plate circuit of relay 73. For convenience I have shown all of the plate circuits connected to a common B-battery 76. Response circuits 21, 22 and 23 are connected to the contacts of electromagnetic relays 81, 82 and 83 in the manner previously described with reference to Figs. 1 and 2.

To explain the mode of operation of the arrangement shown in Fig. 4, it will be presumed that normally no potential difference occurs across the control circuit 10 and that at this time the biasing of relays 71, 72 and 73 is such that the plate currents of these relays are substantially zero. When a potential of magnitude 1 is impressed upon control circuit 10, the plate current of electron relay 71 becomes finite to effect magnetization of magnetic relay 81 and thus effecting closing of response circuit 21. At this time however electron relays 72 and 73 are not operated. When a controlling potential of magnitude 2 is impressed upon control circuit 10, the plate currents of both relays 71 and 72 become finite. Windings 74 and 75 however are differentially related so that assuming that their component fields are substantially equal, the armature of this relay will not be attracted. The component fields of windings 74 and 75 can be readily made equal for this condition, by properly proportioning the same, or by properly proportioning the impedances of electron relays 71 and 72. The winding 74 of relay 82 is energized at this time, to effect operation of electromagnetic relay 82. When a controlling potential of magnitude 3 is impressed across control circuit 10, a finite plate current flows in all relays 71, 72 and 73. Electromagnetic relay 81 still remains inoperative, and magnetic relay 82 is likewise rendered inoperative because of the differential relationship of windings 74 and 75. It is understood of course that at this time the component fields of windings 74 and 75 of magnetic relay 82 are of substantial equal intensity and arranged to neutralize or op-

pose each other. At this time however the current flowing thru winding 74 of relay 83, is sufficient to effect operation of this relay.

It is apparent that my system is susceptible of many modifications and that the principles described can be applied to more complex systems using a greater number of relays than herein disclosed.

I claim:

- 10 1. In a system of the character described, a plurality of electron relays, a plurality of circuits adapted to be selectively affected by said relays, means for controlling said relays, and means interrelating said relays whereby operation of one relay to affect one of said circuits serves to block operation of another relay.
- 20 2. In a system of the character described, a plurality of electron relays, a plurality of circuits adapted to be selectively affected by the outputs of said relays, means for controlling said relays, and means interrelating said relays whereby operation of one relay to affect one of said circuits serves to block the input of another relay.
- 30 3. In a system of the character described, a plurality of electron relays, a control circuit connected to said relays, a plurality of response circuits adapted to be selectively affected by operation of said relays, and means interconnecting said relays whereby only one of said relays is operated responsive to a potential of given magnitude impressed upon the control circuit.
- 40 4. In a system of the character described, three or more relays, a control circuit connected to said relays, a plurality of response circuits adapted to be selectively affected by operation of said relays, said relays being each operative responsive to a different potential impressed upon the control circuit, and means responsive to operation of one of said relays to prevent operation of the other of said relays.
- 50 5. In a system of the character described, three or more relays, a control circuit for affecting said relays, said relays being marginally adjusted for operation responsive to different potentials upon the control circuit, means connecting said relays responsive to operation of a relay adjusted to respond to a given control potential to cause blocking of all relays adjusted to respond to lower control potentials, and response means adapted to be selectively operated by said relays.
- 60 6. In a system of the character described, a plurality of electron relays, a control circuit for affecting operation of said relays, said relays being marginally adjusted for operation responsive to different potentials upon the control circuit, means connecting said relays responsive to operation of a relay adjusted to respond to a given control potential to cause blocking of all relays ad-

justed to respond to lower control potentials, and response means adapted to be selectively operated by said relays.

7. In a system of the character described, a plurality of electron relays, a control circuit for affecting operation of said relays, said relays being marginally adjusted for operation responsive to different potentials upon the control circuit, means connecting a control element of each relay with the output of another relay responsive to operation of a relay adjusted to respond to a given control potential to cause blocking of all relays adjusted to respond to a lower control potential, and response means adapted to be selectively operated by said relays.

8. In a system of the character described, a pair of electron relays each having a pair of control elements and output electrodes, a control circuit connected to a control element of each relay, said elements being differently biased for marginal operation, response means connected to the output electrodes of said relays and selectively operable by the same, and an electrical connection between the output of one relay and the other control element of the other relay.

9. In a system of the character described, an electrical control circuit, a microphone circuit, voice frequency integrating means connecting said microphone circuit to the control circuit, a translating circuit, and a plurality of marginal relays serving to selectively actuate said translating means responsive to different integrated energy values in the control circuit.

10. In a system of the character described, an electrical control circuit, a microphone circuit, voice frequency integrating means connecting said microphone circuit to the control circuit, a translating circuit, and a plurality of marginal relays serving to selectively actuate said translating means responsive to different integrated energy values in the control circuit, and means interconnecting said relays for causing operation of only one relay for any given energy value.

11. In a system of the character described, a plurality of electron relays, input and output circuits for each of said relays, means in the output circuit of each of said relays operative upon energization of its associated relay to block the input of another relay.

12. In a system of the character described, three or more electron relays, input and output circuits for each of said relays, means in the output circuit of each of said relays operative upon energization of its associated relay to block the operation of the other relays.

In testimony whereof, I have hereunto set my hand.

ANTON BUYKO. 130
